UNITED STATES PATENT OFFICE.

THOMAS C. CONRAD, OF PHILADELPHIA, PENNSYLVANIA.

TOY ENGINE.

SPECIFICATION forming part of Letters Patent No. 433,275, dated July 29, 1890.

Application filed April 18, 1890 Serial No. 348,475. (No model.)

To all whom it may concern:

Be it known that I, THOMAS C. CONRAD, of Philadelphia, in the county of Philadelphia and State of Pennsylvania, have invented a new and Improved Toy Engine, of which the following is a full, clear, and exact description.

The object of the invention is to provide a new and improved toy engine which is simple and durable in construction and can be very cheaply manufactured.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of the improvement. Fig. 2 is a plan view of the same. Fig. 3 is an enlarged sectional plan view of part of the improvement. Fig. 4 is an enlarged plan view of a modified form of the same. Fig. 5 is a perspective view of the eccentric strap and rod. Fig. 6 is a perspective view of the guideways. Fig. 7 is a plan view of the valve-stem. Fig. 8 is a perspective view of the cross-head, and Fig. 9 is a transverse section of the improvement on the line *x x* of Fig. 1.

The improved toy engine A is provided with a stick B of suitable length and adapted to be taken hold of at one end and supporting at its other end the engine proper. The latter is provided with a driving-wheel C, journaled at the lower end of the stick B and at one side thereof, either in the manner shown in Fig. 3 or as illustrated in Fig. 4.

As shown in Fig. 3, the hub D of the driving-wheel C fits into a transverse opening B', formed in the stick B, and at the outer end of the said hub is held a washer F, over which is bent one end of a pin E, riveted to the driving-wheel and passing centrally through the hub of the same.

As shown in Fig. 4, the driving-wheel C is mounted to turn on a screw G, screwing transversely into the lower end of the stick B. On the front face of the driving-wheel C is pivotally connected the pitman H, pivoted on the front face of the cross-head I, provided on its

top and bottom with a longitudinally-extending groove I', fitting onto parallel rods or guideways J, preferably formed of a single piece of wire, as is plainly illustrated in Fig. 6, 55 the middle or bent parts J' of the said rods being secured to the side of the stick B by suitable staples K. (See Figs. 1 and 2.)

The outer ends of the rods J are secured to the inner end of a cylinder L, fastened by 60 suitable means to the said stick B. From the cross-head I extends a piston-rod N, passing into the cylinder L and of sufficient length as not to disconnect from the cylinder when the cross-head I is in its outermost position. 65

On the rear face of the driving-wheel C is secured or formed an eccentric O, over which passes an eccentric-strap P, formed, with the eccentric-rod P', of one piece of wire, as is plainly shown in Fig. 5. The end P² of the 70 rod P' is bent inward and forms a pivot for the eccentric-rod, being connected with one end of a lever Q, fulcrumed on a pin Q', secured to the side of the stick B. The upper end of the lever Q is pivotally connected with 75 a valve-stem R, passing into a steam-chest S, formed on top of the cylinder L.

It is understood that a piston is not used in the cylinder L, nor a valve in the steam-chest S, as the two parts referred to would not be 80 visible.

The device is used as follows: The operator takes hold of the upper end of the stick B and rests the periphery of the driving-wheel C on the ground or floor, and when the operator 85 now moves forward and slightly presses on the stick B, so as to hold the driving-wheel C in frictional contact with the floor or ground, then the said driving-wheel turns, and by the pitman H imparts a reciprocating motion to 90 the cross head I, moving the piston-rod N. The turning of the driving-wheel C also imparts motion to the eccentric P, which, by its rod P', imparts a swinging motion to the lever Q, thus imparting a sliding movement to the 95 valve-stem R. It will thus be seen that the movement of the exterior parts of the steam-engine can be readily seen and understood by a child using the toy in the manner specified. The driving-wheel C is preferably counterbalanced, as illustrated in Fig. 1.

Having thus fully described my invention, I

claim as new and desire to secure by Letters Patent—

1. A toy engine comprising a stick, a drive-wheel journaled at one end of the said stick, 5 a pitman connected with the said drive-wheel, a cross-head connected with the said pitman, guideways secured on the said stick and in which slides the said cross-heads, a piston-rod held in the said cross-head, and a cylinder secured to the said stick and into which passes the said piston-rod, substantially as shown and described.

2. A toy engine comprising a stick, a drive-wheel journaled at one end of the said stick, 15 a pitman connected with the said drive-wheel, a cross-head connected with the said pitman,

guideways secured on the said stick and in which slides the said cross-head, a piston-rod held in the said cross-head, a cylinder secured to the said stick and into which passes the 20 said piston-rod, an eccentric held on the said drive-wheel, an eccentric strap and rod connected with the said eccentric, a lever pivoted on the said stick, a valve-stem pivotally connected with the said lever, and a steam-chest 25 held on the said cylinder, substantially as shown and described.

THOS. C. CONRAD.
